UNITED STATES PATENT OFFICE

WILLIAM NEES, OF DREXEL HILL, PENNSYLVANIA

DIE FOR FORMING THROAT SHEETS FOR BOILERS

Application filed July 29, 1927. Serial No. 209,811.

My invention relates to certain improvements in the dies for pressing sheet metal into the form of throat sheets for boilers, etc., particularly boilers of the locomotive type.

5 The broad idea of the invention, however, is fully described and claimed in a copending application filed by me on the 8th day of June, 1927, under Serial No. 197,496.

10 The object of the present invention is to improve the dies for making the internal throat sheet of a locomotive boiler, the sheet being of considerable length and which in the present instance has an expansion corrugation formed therein to allow for the expansion and contraction of the boiler.

15 In the accompanying drawings:

Fig. 1 is a side view of the upper and lower dies for forming the internal throat sheet of a locomotive boiler;

20 Fig. 2 is a face view of the upper die;

Fig. 3 is a face view of the lower die;

25 Fig. 4 is a sectional plan view on the line 4—4, Fig. 2, of the upper and lower dies showing the method of forming the expansion corrugation;

Figs. 5, 6 and 7 are detached end views of the different nose sections; and

30 Fig. 8 is a perspective view of the flanged end of the inner throat sheet of a locomotive boiler.

35 While my invention is particularly adapted for use in forming the throat sheets of locomotive boilers, particularly the inner throat sheet, it will be understood that it can be used for forming flanges on the ends of other semi-cylindrical plates without departing from the essential features of the invention.

40 2 is the lower die shaped as shown in Figs. 1 and 3, it being made in two parts in the present instance. The cavity in the die is semi-cylindrical in form to correspond to the shape of a segmental portion of the tube sheet. The die is flared and so shaped as to form the main flange *d* and side flanges *e*—*e*.

45 The throat sheet is corrugated as at *f*—*f*, directly back of the flange *d* so as to allow for expansion and contraction, and the lower die has a projecting rib 3 at each side, which is tapered as shown and coincides with a groove 4 in the upper die 5. The front end 6 of the

lower die is at right angles to the inclined portion 7 of the die and the two surfaces are connected by the curved section 8 of the radius shown.

55 The upper die 5 is shaped as shown in Figs. 1 and 2, and the front end of the die has two pairs of ribs 14—14 spaced apart and centrally located ribs 16—16. The body portion of the die 5 also has side flanges 17. The flanges 14—14 are spaced apart to receive the extensions 10 of the nose section 9^a of the upper die, which, in the present instance, is made in two sections, and the ribs 16—16 are spaced apart to receive the portions 11 of the upper die.

60 The extensions 10—10 are secured to the flanges 14 by bolts 15, while the extensions 11 are secured to the flanges 16 by bolts 18. Bolts 19 secure the horizontal flanges of the nose section to the flanges on the body portion of the upper die, while bolts 20 secure the inclined flanges of the two parts together. This construction is very substantial and one which will allow for the removal of one size nose section and the placing of a different sized nose section.

65 In making the throat sheet as shown in Fig. 8, various operations are necessary and different lengths of nose pieces are provided. The nose piece shown in Fig. 5 is short and is for the first operation. The nose piece shown in Fig. 6 is of medium length and is for the second operation, while the nose piece shown in Fig. 7 is of full length and is used on the third operation for finishing the bending of the flange.

70 It will be understood that the body of the throat sheet is bent to the proper curve by ordinary bending rolls, and the dies above-described are used only to form the flanges on the ends of the throat sheet and to form the diminishing corrugations on the throat sheet back of the flanges. It will also be understood that in the shaping of the upper and lower dies to form the throat sheet, the expansion joints may be omitted where a joint is unnecessary.

75 By removing the bolts 15, 19 and 20, the nose piece sections 9^a can be detached from the body portion of the upper die and other sec-

tions can be substituted therefor, by simply using an overhead crane which lifts one section out of position and moves another section into position.

5 It will be realized that the dies are extremely heavy, and even the nose section to be adjusted properly is more than a man can handle. The nose piece can also be detached from the body of the die when it is found unnecessary owing to the peculiar throat sheet or other form to remove the formed blank from the dies without raising the upper die to its extreme height.

10 The invention is likewise particularly adapted for use in connection with standard presses having their given lifts.

I claim:

1. The combination in an upper die for forming throat sheets of locomotive boilers and the like, said upper die having three sets of spaced ribs at one end, of a nose piece made in two sections, each section having extensions adapted to the spaces between the ribs of the upper die, both the die and nose piece having horizontal and angular ribs; bolts securing the ribs of one section to the other section; and bolts securing the extensions of the nose piece to the ribs of the upper die.

20 2. The combination of a lower die having a recess formed therein, and having an inclined portion against which a flange is formed, and an inwardly projecting tapered rib on the lower die; and an upper die having a nose piece and grooved at each side to receive the tapered projecting rib which will form corrugations in a throat sheet directly back of its flange.

WILLIAM NEES.
